UNITED STATES PATENT OFFICE.

BERNT PEDERSEN, OF MOUNT VERNON, NEW YORK.

CARBURETER.

1,238,433.

Specification of Letters Patent. Patented Aug. 28, 1917.

Application filed October 26, 1915. Serial No. 57,912.

To all whom it may concern:

Be it known that I, BERNT PEDERSEN, a citizen of the United States, residing at Mount Vernon, in the county of Westchester and State of New York, have invented certain new and useful Improvements in Carbureters, of which the following is a full, clear, and exact description.

This invention relates to carbureters for internal combustion engines.

The primary object of the invention is to provide a carbureter in which the air and fuel are supplied to the mixing chamber in finely divided particles and an intimate mixture of the air and fuel obtained.

Another object of the invention is to provide an improved form of throttle valve for controlling the admission of the mixture to the manifold of the engine. A still further object of the invention is to provide an improved form of control for the fuel supply so that the same may be varied at will. A still further object of the invention is to provide improved means for admitting an additional supply of air to the carbureter when the engine demands the same, which may be used in combination with the control of the fuel supply for same, to obtain a proper combustible mixture under all conditions of load and speed of the engine.

With these and other objects in view, which will be obvious to one skilled in the art, the invention consists of the constructions which will be hereinafter described, and particularly pointed out in the appended claims. In the accompanying drawings I have disclosed a preferred embodiment of the invention, in which—

Figure 1 shows an elevation of a carbureter constructed in accordance with the principles of my invention.

Fig. 2 is a central vertical section through such a carbureter, and

Fig. 3 is a transverse section through the carbureter casing at a point just above the throttle.

Referring to the drawings, a pipe 1 is shown, which is adapted to be connected to the manifold of the engine. The carbureter comprises a casing, the structural details of which may be varied, and in the form shown consists of an upper section 2, having a flange 3, by which it is united to a flange 4, carried by the pipe 1. The upper section 2 of the casing is substantially of a bell or dome shaped configuration, and has

its lower end exteriorly threaded as at 6. The intermediate section 7, is substantially cylindrical in shape, and is of a less diameter than the mouth of the bell shaped section 2, the section 7 being provided with a laterally projecting annulus 8, which carries an up-standing flange 9 engaging the threaded surface 6, of the section 2. The lower section of the casing comprises a threaded cap 10, which closes the bottom of the section 7, and is provided with a plurality of apertures or openings 11, which serve as a means to admit the supply of air to the carbureter.

Projecting laterally into the section 7 adjacent its lower end is a pipe or conduit 12, through which the fuel is supplied to the carbureter from any suitable reservoir (not shown.) The inner end of this pipe is closed as at 14, and is provided with a conically shaped aperture or opening 15, which forms a seat for a needle valve 16. The valve 16 is threaded into a bushing 17, one end of which also extends into the section 7 at a point diametrically opposite the pipe 12. The inner ends of the pipe 12, and the bushing 17, which lie within the section 7 of the casing, are threaded into a sleeve 19. These ends do not abut in the middle of the sleeve, but are spaced sufficiently apart to provide a chamber or well 20, which is filled by fuel passing through the inlet 15. Positioned directly above this chamber, and preferably threaded into a suitable opening in the sleeve 19 is fuel nozzle 21 which is provided at its upper end with a cone shaped opening controlled by a needle valve as will be hereinafter described. Surrounding the opening in the nozzle 21 is a distributing plate 22, consisting of a circular disk. The distributing plate is preferably provided with a plurality of perforations 23, which are of relatively small diameter, the purpose of which will be clear from the description of the operation of the carbureter.

Located within the section 7 of the outer casing is an inner casing consisting of two hollow cylindrical sections 24, and 25. The top section 24 is of less diameter than the section 7, which leaves an annular space or chamber 26 between these parts, the upper end of which chamber is closed by an offset extension 27 integral with the section 7. The bottom section 25 forms a tube which is only of slightly larger diameter than the

distributing plate 22 which it completely surrounds. This tube extends from a point substantially on a level with the distributing plate downwardly to the sleeve 19 and has 5 its lower end fitted over an annular flange 29, carried by a boss on the sleeve 19. Longitudinally arranged elongated slots 30 are provided in the section 25, which serve to conduct the supply of air which enters the 10 casing through the apertures 11 to a point below the distributing plate 22. The sections 24 and 25 of the inner casing are joined by an annular shoulder 31, which is also provided with a plurality of openings 15 32, through which the air may enter the interior of the tubular member 24.

The passage between the two tubular sections 24 and 25 is closed by a perforated diaphragm or partition 35 which in the 20 construction shown is substantially dome shaped, and forms a top for the section 25. This partition may also be regarded as forming the bottom of the mixing chamber which is composed of the section 2 of the outer casing and the section 24 of the inner casing. The section 25 may then be regarded as the conduit which conducts the air to the mixing chamber.

The opening in the fuel nozzle 21, is controlled by a needle valve 40, which is slidably mounted upon a pin 41 and passes through a suitable opening in the partition 35. The upper end of the pin 41 is supported in a post 41' which passes through 35 the center of disks 42 and 43. These disks constitute the throttle valve, and will be hereinafter described.

Surrounding the pin 41, and interposed 40 between the plate 43 and the upper end of the needle valve, is a spring 44, which exerts its tension to press needle valve 40 into the cone shaped opening at the top of the nozzle 21 and to maintain the same closed when the carbureter is not working. The 45 valve is opened against the tension of this spring by the pressure of the mixture against a disk 45 carried by the needle valve 40. This disk is also provided with a plurality of small openings or apertures 46, through which the mixture of air and fuel passes.

As before described, the throttle valve consists of two circular plates or disks 42 and 43, one of which, as for example, disk 50 42, is stationarily mounted in the section 2 upon the post 41' and is held against the disk 43 by the adjustable spring 42' which surrounds the post 41'. The disk 43 is adapted to rotate on this post. The disks 60 42 and 43 are of a similar construction and each is provided with a plurality of segmental shaped openings 48. As shown in Fig. 3, these segmental openings in each of the plates are of substantially the same size 65 and are so formed that if each plate is re-

garded as being divided into sectors, alternate sectors will be provided with the segmental shaped openings, while the intermediate sectors will be solid and adapted to close the openings in the other plate when the valve is in its closed position.

A lug 49 extends downwardly from the disk 43, and has secured to it an arm 50 which passes through a suitable slot 51, in the section 2. A rod 52 is secured to the outer end of this arm at one end and is adapted to be connected at its other end to any suitable system of links or gearing, (not shown) which, when the carbureter is used with an automobile, would have a manually operable part positioned either on the dashboard or the steering post, so that the position of the throttle valve may be varied at will.

Resting upon the annulus 8 is a rotary 85 ring 53, which is held in position by a washer 54, threaded upon the outer face of the extension 27. The annulus 8, and this ring 53 are each provided with a plurality of openings 55, which are adapted 90 to be brought into and out of alinement upon a slight angular movement of the ring 53. These apertures 55 provide means for supplying an additional amount of air to the carbureter, and will be referred to in 95 the description of the operation. Secured to the ring 53 is a bolt 56 which passes through a suitable slot in the annulus 8. Secured to the lower end of this bolt is a member 57 having two arms 58, which extend on each 100 side of the arm 50 as is shown in Figs. 1 and 3. The arms 58 are spaced a sufficient distance apart so that the arm 50 which actuates the throttle valve is moved to a position in which the throttle valve is in substantially half open position before the 105 openings 55 commence to come into alinement.

The needle valve 16 is also adapted to be adjusted at will to regulate the supply of 110 fuel. This is accomplished by means of an arm 59, attached to the end of the needle valve, which is connected to a rod 60, forming a part of a system of linkage, not shown, which similar to the rod 53 is controlled 115 from the steering post or dash-board of the automobile. The system of linkage should be designed to impart an angular movement to the arm 59, which will, in turn, rotate the needle valve in its threaded bushing to 120 advance or retract it, and thereby vary the area of the inlet opening 15.

The operation of the carbureter will now be described. Assuming that the engine to which the carbureter is attached is at rest, the needle valve 40, will, due to the tension of the spring 44, be held against the opening in the fuel nozzle 21, to maintain the same closed. In order to prevent leakage, the arm 59 should also be moved to a pos- 130

tion in which the needle valve 16 will engage its seat, and close the inlet opening 15. When it is desirable to start the engine, the throttle valve is partially opened as is the usual practice, which is accomplished by moving arm 50 to an intermediate position. It may be here stated that this initial movement to the throttle valve is not sufficient to cause the arm 50 to engage one of the bifurcated arms 58 to cause the auxiliary air inlets 55 to be opened. The inlet valve 16 is also adjusted to a position in which fuel is permitted to enter the carburetor through the inlet opening 15, which fuel enters the well or chamber 20, and passes up through the fuel nozzle 21, where it will spread out over the distributing plate 22 in a thin film when the valve 40 is opened. No float chamber is necessary if a gravity feed is produced by placing the tank or reservoir containing the fuel connected to the conduit 12, above the level of the top of the nozzle. If this is not possible, some means should be employed to create a pressure sufficient to raise the fuel to a point above the top of the fuel nozzle. The amount which it is necessary to open the needle valve 16 may be determined by experience in the first instance, and thereafter, a gage or index of some character be employed which will permit the operator to always move the valve to the proper position. The engine is then cranked which will create a suction within the carburetor, causing the air to enter the same through the openings 11 in the cap 10. The air thus admitted to the section 7 of the carburetor then passes through the elongated openings 30 in the section 24 of the inner casing. Since these openings are below the distributing plate 22, the air will then pass up and around the peripheral edge of this plate, and through the perforations 23 therein. The air then passes through the perforated partition 35 into the section 24 of the inner casing, and thence upwardly through the mixing chamber. The pressure of the air against the baffle plate or disk 45, is sufficient to lift the needle valve 40 against the tension of the spring 44, so that the fuel will spread out over the distributing plate 22 in a thin film. The suction in the carburetor is continued, and more air will then enter through the openings 11 and 30, as before described, and then pass upwardly, around, and through the perforations in the distributing plate 22. The film of gasoline which is now spread out over the top of the distributing plate will be absorbed by the air in its passage, and this incomplete mixture of air and fuel will be forced through the perforations in the partition 35 which forms the bottom of the mixing chamber. The result is a breaking up of air and fuel into minute particles, which will cause a more rapid and thorough absorption of the

fuel by the air than would occur if the mixture were permitted to unobstructably enter the mixing chamber. The mixture of the fuel and air then passes through the disk or baffle plate 46 where it is again divided, 70 which will, therefore, serve in the same manner to produce an intimate mixture of the fuel and air. The proper combustible mixture produced in the mixing chamber will then pass through the partially opened 75 throttle valve to the manifold of the engine. I have found that the mixture of the air and fuel in the manner described takes place more thoroughly and rapidly, if the mixture of fuel and air is forced through the perforated partition 35 under considerable pressure, and I have also found that the air more readily takes up the fuel or oil if it is carried past the distributing plate under considerable pressure. It is for this reason that 80 I have made the tubular section 25, of only slightly greater diameter than the distributing plate, and have made the partition 35, which forms the bottom of the mixing chamber, of considerable less area than the cross-sectional area through the body of the mixing chamber. This construction is also advantageous for the reason that if after the mixture of air and fuel has passed through the perforated bottom 35 of the mixing 85 chamber it is permitted to expand, it will cause a more complete absorption of the fuel by the air. In the description of the device, I have described one specific construction for obtaining these advantages, but 90 it is intended that any construction in which the air and fuel are led into the mixing chamber, through a perforated bottom of constricted area, shall come within the scope of this invention, as set forth in the appended 95 claims.

After the engine has started, various conditions of speed and load occur which make it desirable to adjust the carburetor. For example, supposing the engine is running under full load as it does when an automobile is climbing a hill. Under these circumstances the throttle valve is moved to its full open position which will cause the openings 55 controlling the auxiliary air supply 110 to come into alignment, permitting an increased amount of air to enter the mixing chamber of the carburetor. In order to obtain the proper combustible mixture it is then necessary to provide a greater amount of fuel, for otherwise the mixture would be lean, which is objectionable. The increased amount of fuel necessary is supplied by opening the needle valve 16, which may be controlled at will by the operator. The 115 amount of opening of the needle valve, which will give the necessary increased supply of fuel without flooding the carburetor, may be determined by experience or by the use of a proper index. To prevent any con- 120

density of the fuel adjacent the shoulder 31 which joins the sections 24 and 25 of the inner casing together, which might otherwise occur since a pocket is formed at that 5 point, the openings 32 are provided through which some of the air within the section 7 may pass. For other conditions of load and speed the needle valve 16 and the throttle valve and auxiliary air openings 55, may 10 be regulated so that in each instance a proper combustible mixture is obtained.

I claim:

1. In a carbureter, an intake pipe, a globular casing narrow at one end and wide at 15 the other end adapted to have its narrow end secured to said intake pipe, a throttle valve in the lower wide end of the casing comprising two circular plates having openings therein adapted to be brought into and 20 out of alinement upon relative movement of said plates, a cylindrical casing secured to the wide end of said globular shaped casing, said cylindrical casing being of less diameter providing an annular shoulder between 25 said casings, said annular shoulder having air openings therein, an annular plate having air openings therein coöperating with said air openings in said annular shoulder, an inner casing within said cylindrical cas- 30 ing, a fuel nozzle mounted in said casing, a fuel conduit extending through said cylindrical and inner casings in open communication with said fuel nozzle, a valve mounted upon said cylindrical casing for controlling 35 the supply of fuel from said conduit to said nozzle, said nozzle having a distributing plate on a level with and surrounding the opening in said nozzle, said nozzle opening being unrestricted during the normal opera- 40 tion of the carbureter to permit the fuel to flow from said nozzle over said distributing plate, said distributing plate being only of slightly less diameter than the said inner casing, a suction operated valve for control- 45 ling said fuel nozzle opening, and said cy-

lindrical and inner casings having air openings therein.

2. In a carbureter, an intake pipe, a globular casing narrow at one end and wide at the other end adapted to have its narrow end secured to said intake pipe, a throttle valve in the lower wide end of the casing comprising two circular plates having openings therein adapted to be brought into and out of alinement upon relative movement of said plates, a cylindrical casing secured to the wide end of said globular shaped casing, said cylindrical casing being of less diameter providing an annular shoulder between 50 said casings, said annular shoulder having air openings therein, an annular plate having air openings therein coöperating with said air openings in said annular shoulder, a common means for moving said annular plate and one of said circular plates, an inner 55 casing within said cylindrical casing, a fuel nozzle mounted in said casing, a fuel conduit extending through said cylindrical and inner casings in open communication with said fuel nozzle, a valve mounted upon said 60 cylindrical casing for controlling the supply of fuel from said conduit to said nozzle, said nozzle having a distributing plate on a level with and surrounding the opening in 65 said nozzle, said nozzle opening being unrestricted during the normal operation of the carbureter to permit the fuel to flow from said nozzle over said distributing plate, said distributing plate being only of slightly less 70 diameter than the said inner casing, a suction operated valve for controlling said fuel nozzle opening, and said cylindrical and inner casings having air openings therein. 75

In witness whereof, I subscribe my signature, in the presence of two witnesses.

BERNT PEDERSEN.
